UNITED STATES PATENT OFFICE.

JAMES McVANE, OF BOSTON, MASSACHUSETTS.

STOCK-REST.

SPECIFICATION forming part of Letters Patent No. 286,462, dated October 9, 1883.

Application filed May 16, 1883. (Model.)

To all whom it may concern:

Be it known that I, JAMES McVANE, of Boston, in the county of Suffolk and State of Massachusetts, have invented a new and useful 5 Improvement in Stock-Rests, of which the following is a full, clear, and exact description.

My invention seeks to provide a new and improved stock-rest for carpenters' use, having such construction that it shall be conveniently portable, and at the same time practicable, and such that it may be easily adjusted to suit the width, thickness, and length of the stuff being worked.

Reference is to be had to the accompanying 15 drawings, forming a part of this specification, in which similar letters of reference indicate corresponding parts in both the figures.

Figure 1 is a perspective view, showing my new and improved stock-rest as it appears 20 when attached to the bench for use; and Fig. 2 is a perspective view of the sliding pawl-block that carries the vertical bar of the stock-rest.

A is the vertical main bar of the stock-rest. 25 This bar is formed with the series of notches *a*, so that it may be held at any desired elevation within its limit of movement by the pawl *c*, pivoted to the block *B*, in the dovetailed groove *b* of which block the said bar *A* is placed and held.

The block *B*, besides being formed with the vertical dovetailed groove *b*, is formed with the horizontal T-shaped groove *d* in its opposite face, whereby the block is adapted to fit 35 upon the guide-rail *C*, which is T-shaped in cross-section. This guide-rail *C* is made in sections, each section being about two and one-half feet in length, suitable to be conveniently packed in a tool-chest, and the sections are 40 adapted to be secured to the side board, *f*, of the bench *D* by the screws *e e*, so that they may be detached at pleasure.

The upper end of the vertical bar *A* is formed or provided with the cross-head *A'*, that 45 supports the timber being planed or otherwise

worked, and this cross-head is by preference made T-shaped in cross-section, and has the dog *E* fitted upon it for holding the timber upon the cross-head against lateral movement, and this dog is made movable on the cross-head, so that it may be adjusted to suit various thicknesses of timber, and is provided with the set-screw *g*, whereby it may be secured at any desired position upon the cross-head *A'* as the timber requires. 50

The vertical bar *A* will be about one foot in length, and the guide-rail *C* will be secured to the side board, *f*, of the bench *D* about nine inches from the top of the bench, so that the bar may be raised in block *B* for very narrow 60 stuff, and lowered therein for working very wide stuff.

The block *B* and guide-rail *C* will by preference be made of cast-iron, while the other parts of the rest will be by preference made 65 of malleable cast-iron.

Constructed in this manner it will be seen that the rest is adapted for all of the adjustments required, and the changes may be easily effected. Besides, it may be easily detached from the bench, and all taken apart and packed in small space in a tool-chest for carrying from place to place, and it is cheap, 70 strong, and durable.

Having thus described my invention, what I 75 desire to claim, and secure by Letters Patent, is—

A vertical bar, having notches at intervals on one side, and a top cross-head carrying an adjustable slide-dog, in combination with a 80 block having a front vertical slideway for the bar, a horizontal rear T-groove carrying a guide-rail, and a front pawl pivoted to allow its front end to be entered in or removed from said notches, substantially as shown and described. 85

JAMES McVANE.
